CLAIM

The ornamental design for a wide format scanner or printer, as shown and described.

DESCRIPTION

FIG. 1 is a front perspective view from above and to the right of a wide format scanner or printer, according to the invention;

FIGS. 2 and 3 are right-hand and left-hand elevational end views of the invention;

FIG. 4 is a front perspective view from above and to the left of the invention;

FIG. 5 is a top view of the invention;

FIG. 6 is a front elevational view of the invention;

FIG. 7 is a rear elevational view of the invention;

FIG. 8 is a front perspective view of a second embodiment of the invention;

FIG. 9 is a front perspective view from above and to the right of the second embodiment of the invention; and,

FIG. 10 is a right-hand end elevational view of the second embodiment of the invention, the left-hand end elevational being identical to FIG. 2.

Broken lines and unshaded portions contained within broken line is not claimed.

The appearance of the bottom of the invention is not claimed.
